ANODE DEVICE

Alexis Basilewsky, New York, N. Y., assignor to
Solvay & Cie, Ixelles-Brussels, BelgiumApplication July 25, 1949, Serial No. 106,723
In Belgium October 23, 1944

1 Claim. (Cl. 204—286)

1

My invention consists in a new and useful improvement comprising means for mounting a stem for the anode of an electrolytic cell in which gas is generated, a method of and means for initially assembling the stem and its supporting ring, and means for adjusting the stem. The invention is concerned particularly with the control of the space between the electrodes in an electrolytic cell of the mercury type in which the anode is a horizontally disposed graphite plate and the cathode is a layer of mercury on the bottom of the cell.

This application is a continuation in part of my two co-pending applications, now abandoned, Serial Number 620,009, filed on October 3, 1945, 15 and Serial Number 728,307, filed on February 13, 1947.

In electrolytic decomposition of alkali halides, for example, sodium chloride, an aqueous solution thereof is introduced into a cell, overlying a mercury layer which serves as a cathode. An anode plate of graphite or the like is disposed in a pool of the solution. Passage of direct current between the anode and the cathode brings about decomposition of the metal halide with resulting evolution of chlorine gas which rises to the top of the cell in a vapor space overlying the electrolyte. Alkali metal, for example, sodium, goes to the mercury cathode and amalgamates therewith. For a normally well-designed cell, the amount of alkali metal decomposed per hour depends on the amount of current which goes through the electrolyte. The drop that occurs between anode and cathode depends on different factors which are:

1. The theoretical voltage of the electrolytic decomposition of the alkali metal halide;
2. The contact resistance between the several electric conductors bringing the current to the electrodes;
3. The electric resistance of the solution (electrolyte) to the passage of the current.

As the consumption of electric power, per unit of the product manufactured, will be the result of the multiplication of the current by the total voltage, both of these factors should be reduced to a minimum in a practical way. The present invention provides means to minimize the drop of voltage between the electrodes, and more particularly the resistance opposed by the electrolyte to passage of the current. This resistance depends on the current density, the conductivity of the electrolyte and the space between anode and cathode. Although the current density and the conductivity of the electrolyte will depend on the general conditions of the process, the space between the electrodes should be as small as possible. During the operation of the process,

5 evolution of chlorine on the graphite anode causes consumption of this material which increases the space between the electrodes, and requires, after a certain time, adjustment of the anode to prevent excessive drop of voltage which would result in undue consumption of electric power per unit 10 ton of the product manufactured. This necessity for adjusting the anode to determine the space between anode and cathode has been a problem for all designers of electrolytic cells, and has been dealt with in different ways, depending on the possibilities of the available technique.

15 The materials of the cells must resist the tendency to corrosion caused by wet chlorine, one of the most active chemicals. Moreover, the chlorine produced must be as concentrated as possible, and all leakage of chlorine into the atmosphere must be avoided because chlorine is a toxic gas even in smallest concentrations in the air and it causes corrosion of metallic parts of the apparatus. In the beginning, cells were made of concrete, and the anode stems were sealed by means of cement to the top of the cell and the current was led to the anode by means of a copper conductor fixed on a graphite anode stem. To control the space between anode and cathode, one 20 had to remove the cover of the cell and allow the anode to descend by changing spacers. Gas-tightness was secured by means of suitable mastic, and to avoid any leakage of chlorine into the atmosphere, the cell was maintained under reduced pressure. This form was the most usual and the most widely used by users of electrolytic cells. It is obvious that to control the space 25 between anode and cathode the cell had to be rendered inactive, opened, the stem adjusted, and the cell closed, all of which required a considerable amount of time and consequently reduced the working time of the cell. Such a method 30 could be used with cells working with low current densities, as for instance 100 amperes per sq. ft., when the loss of electric energy was proportionately not so important. Actually when the current densities are increased, this problem becomes 35 more acute because the loss of electric energy becomes more serious and the consumption of the graphite is increased more and more quickly as the current density grows. Many inventors tried to develop devices for quicker and more efficient 40 control of the space between the electrodes without having to render the cell inactive, and with a minimum of working power. The fact that modern cells generally use ebonite-lined steel, permits inventors to use more versatile 45 equipment. In Germany, the anodes were suspended from a cover of ebonite-lined steel through a packing gland providing practically 50 gas-tightness of the joint and the current was 55 suspended from a cover of ebonite-lined steel through a packing gland providing practically gas-tightness of the joint and the current was

2

supplied to the graphite stems through a copper bar attached by bolts. This device allows control of the anode-cathode distance without opening the cell, but it necessitates relatively expensive glands which must be ebonite-lined to prevent corrosion by chlorine, and specially impregnated packings which are attacked by chlorine after a certain time. Moreover, the control of the space requires a rather long operation of unscrewing the gland and the attached copper bar and rescrewing it after the space has been corrected.

To avoid such difficulties and to provide a device which is cheap and easily handled, applicant has found as a result of his experience that a simple graphite ring in which a graphite stem is pressed can assure the desired gas-tightness, a satisfactory transmission of current and a simple way to control the space between the electrodes, without interfering with the operation of the cell. In the improved device, hereinafter fully described, a graphite rod to serve as the anode stem is pressed through a graphite ring under conditions which will be fully described. The graphite ring is mounted on the cell with a gasket of rubber or other material resistant to chlorine which assures a seal to prevent escape of gas from the cell. The electric current is brought to the anode by a conductor mounted on the ring and the assembled ring and conductor are removably clamped by a plate and bolts. Electrical insulation of the graphite ring from the cover of the cell is secured by a device fully explained below, and between the plate and the conductor there is also an insulation gasket, and the bolts are insulated in any convenient and well-known way. The current passes from the conductor to the graphite ring and then to the graphite rod and the anode, with the smallest loss of voltage possible, and it is obvious from the foregoing description that the device will cost less than all of the other proposed devices.

Contrary to the usual opinion, I have found by experience that graphite is sufficiently elastic to permit it, without rupture, to stand considerable pressure of the rod against the ring. The internal diameter of the graphite ring is less than the external diameter of the rod. A chart in which the differences of the two diameters are the abscissas and the force required to press the rod through the ring are the ordinates shows a straight line indicating the amounts of force suitable for the purpose desired. I have found that to obtain good results this force should be between 400 and 1200 pounds depending on the diameter differences which gives satisfactory mounting, avoids too delicate machining of the graphite parts, and allows an easily controlled assembly of rod and ring by measuring the force required to pass the graphite rod into the graphite ring. Since graphite is porous, it is necessary, to avoid any diffusion of chlorine through the pores, to impregnate the graphite ring and the graphite rod with a suitable impregnating medium which will not harm the graphite, prevent movement of the rod through the ring, or provide a high electrical contact resistance. Such product can be chlorinated naphthalene or melted paraffin wax.

In the drawings:

Fig. 1 is a vertical section of the cell, the cathode, the anode, the stem for the anode, and the mechanism for adjustably mounting the stem.

Fig. 2 is a side elevation of a tool applied to the stem for adjustment thereof.

Fig. 3 is a horizontal section on the line 3-3.

of Fig. 2, in the direction of the arrows, a portion being broken away.

Fig. 4 is a horizontal section on the line 4-4 of Fig. 2, in the direction of the arrows.

Fig. 5 is a fragmentary, top plan of a cell provided with a plurality of cathodes and anodes, portions of the casing of the cell being removed to disclose a number of the anode stems and the mechanism for their adjustable mounting.

Fig. 6 is a diagrammatic, vertical section of a mechanism for the initial assembly of the anode stem and its graphite ring.

Fig. 7 is a pressure chart indicating, in inches and pounds, the proper degrees of pressure for the initial assembly of anode stems and rings of given dimensions.

As illustrated in the drawings, the cell 1 (Fig. 1) has a cover 2 removably clamped thereon, and a gasket 3 on the upper edge of the cell 1 to provide a gas-tight seal. The cover 2 has a circular orifice 2-a, and a lining 4 of suitable electric insulating material, such as ebonite or glass, which passes through the orifice 2-a and has an annular portion 4-a overlying the cover 2 peripherally of the orifice 2-a. Imposed on this portion 4-a is the graphite ring 5 with a suitable electric insulating gasket 6, such as impregnated asbestos, disposed between portion 4-a and ring 5, the orifice 2-a and the ring 5 being co-axial. A suitable electrical conductor ring 7 is mounted on the ring 5 co-axially therewith and has a suitable electric lead 7-a. A suitable plate 8 serves to clamp the rings 5 and 7 on the cover 2 by means of bolts 9 with nuts 9-a suitably insulated and an insulating gasket 10 is interposed between the ring 7 and the plate 8. The plate 8 has an orifice 8-a co-axial with rings 5 and 7. If desired, the plate 8 being metallic may be mounted directly on the ring 5, ring 7 and gasket 10 being omitted, and the lead 7-a being connected to plate 8, the plate 8 being suitably insulated from bolts 9.

Suitably mounted on the cover 2 of the cell 1 there is a suitable framing 11 supporting a removable casing 12.

Overlying the bottom of the cell 1 there is a mercury layer 13 operating as the cathode with a suitable electric lead 13-a passing out of the cell 1, through a sealed joint or by any other suitable means. The anode 14 is suspended in the cell 1 so that its lower face 14-a is closely adjacent the cathode 13, by the graphite stem 15, the reduced portion 15-a of the stem 15 being received in a drive-fit in a socket 14-b in the anode 14. The stem 15, passing loosely through the orifice 2-a of the cover 2, is engaged in a gas-tight fit by the graphite ring 5, and extends loosely through the ring 7 and the orifice 8-a of the plate 8, projecting upwardly of the plate 8, its slightly tapered upper end 15-b being disposed slightly below the casing 12.

The tool T for adjusting the stem 15 and anode 14 (Figs. 2, 3 and 4) has a frame 16 comprising a horizontal beam 17 from the ends of which depend legs 18 having on their lower ends lugs 19, respectively, which co-act with latches 20 fixed on the plate 8, by which the tool T can be removably mounted on the plate 8. Suitably threaded in the beam 17 there is a rod 21 having on its upper end an operating handle 22. The rod 21 has on its lower end a head 23. Loosely carried on the rod 21, above the head 23, is a collar 24 having depending fingers 25 carrying a resilient clamping ring 26 having lugs 27 and 28 (Fig. 4). A fork 29 is mounted on lug 27 and

loosely embraces lug 28. Journaled in the legs of the fork 29 (Fig. 2) there is a shaft 30 extending upwardly through and journaled in the beam 17, and provided on its upper end with an operating handle 31 adjacent the operating handle 22 of the rod 21. The shaft 30 has fixed thereon, between the legs of the fork 29, a cam 32 co-acting with lug 28 (Fig. 4) to operate the clamping ring 26.

As shown in Fig. 5, a cell 100 can be provided with a considerable number of cathodes and anodes with anode stems having my improved adjusting mechanism. The cell 100 has a casing comprising individually removable portions 101 so that a plurality of anode stems are accessible by removal of certain portions 101. There is illustrated in Fig. 5 means whereby four electric leads 7-a to four anodes, respectively, can be provided with a single electric switch. As illustrated, the leads 7-a have contacts 7-b co-acting with a manual knife switch 102 suitably pivoted on cell 100 and having attached thereto a suitable electric lead (not shown).

Fig. 6 illustrates diagrammatically a device for the initial assembly of the graphite ring 5 and the graphite stem 15. The device comprises a press having a bed 200 with a seat 201 to receive the ring 5 therein and a bore 202 co-axial with seat 201. The bottom 202-a of the bore 202 is disposed below the bottom 201-a of the seat 201 at a precise distance for a purpose presently to be explained. The press has a reciprocatable head 203 comprising a slidably mounted casing 204 charged with a suitable fluid, such as oil, forming a liquid mass 205 upon which impinges a piston 206 reciprocated by any suitable means such as a manual lever (not shown). A manometer 207 is provided to indicate in pounds the pressure exerted by the head 203 on the stem 15 to press it into assembly with the ring 5. The manometer 207 has marks 207-a and 207-b to indicate the minimum and maximum degrees of desirable pressure.

I will now describe the novel method of initially assembling the supporting ring 5 and the anode stem 15, which can be practiced by the use of the novel means illustrated in Fig. 6. The ring 5 is placed in the seat 201 of the bed 200. The stem 15 is positioned co-axially of ring 5 and bore 202 of the bed 200, its tapered end 15-b being introduced into the ring 5. The head 203 of the press is lowered by its actuating lever, pressing the stem 15 through the ring 5. It is obvious that the stem 15 is pressed downwardly by the casing 204 which is moved downwardly by the pressure exerted by the piston 206 reciprocated by the lever (not shown) and transmitted by the mass of liquid 205, the manometer 207 indicating the degree of pressure exerted. The depression of the stem continues until the tapered end 15-b of the stem 15 passing from the ring 5 a precise distance through bore 202 is brought into contact with the bottom 202-a of the bore 202 in the bed 200. This contact is indicated by the manometer 207 due to excessive pressure on mass 205 when the stem 15 has been seated in bore 202. The above-described steps, of my improved method of initially assembling the ring 5 and the stem 15, assure a precisely determined disposition of the stem 15 in the ring 5 for a purpose presently to be explained.

As previously mentioned, to effect the desired relation of the ring 5 and the stem 15, the internal diameter of the ring 5 must be less than the external diameter of the stem 15. It is

obvious that the degree of variation of these diameters determines the degree of pressure required to effect movement of the stem 15 relative to the ring 5. I have found that good results are obtained when this degree of pressure is between 400 and 1200 pounds and experience has shown that a graphite ring 1.8 in. thick and having an outside diameter of 5.3 in. should have an inside diameter of 2.95 in. and that outside diameter of the graphite stem should be 2.95 plus in., the excess of the external diameter of the stem over the internal diameter of the ring varying from .0018 in. to .0081 in. I have shown in the chart (Fig. 7) the several degrees of pressure required to press the stem 15 through the ring, dependent upon said excess.

Calling D the external diameter of the stem 15 and D' the internal diameter of the ring 5, then

$$D-D' \geq 0.00001D$$

and

$$D-D' \leq 0.01D$$

Calling Δ the diameter of the largest inscribed circle on the ring, then Δ should be approximately 1.79D.

Calling H the thickness of the ring, or the distance between the two faces of the ring, then H should be approximately 0.6D.

It is obvious that the above-stated satisfactory dimensions correspond to these stated limits. D-D' is between 0.0018 and 0.0081 inches. This is well between the limits, that is to say, when D=2.95, then

$$\text{Minimum } D-D' \geq 0.00001 \times 2.95$$

that is

$$D-D' \geq 0.0000295 \text{ inch}$$

$$\text{Maximum } D-D' \leq 0.01 \times 2.95$$

that is

$$D-D' \leq 0.0295 \text{ inch}$$

It is obvious that 0.0018 inch and 0.0081 inch are between the limits.

A amounting to 5.3 inches has approximately the proper dimension, since

$$1.79D \text{ or } 1.79 \times 2.95 = 5.28 \text{ inches}$$

Also H amounting to 1.8 inches has approximately the proper dimension, since

$$0.6D \text{ or } 0.6 \times 2.95 = 1.77 \text{ inches}$$

When the ring 5 and the stem 15 have been initially assembled, as above described, the parts are assembled in the cell 1 as shown in Fig. 1. It is obvious that, since the total length of the stem 15 and the thickness of the anode 14, before use, are known, and the anode 14 is mounted on the end 15-a of the stem 15, and the ring 5 is disposed on the stem 15 at a precise position determined by the length of the bore 202, when the ring 5 is seated upon the cover 2 of the cell 1, the space between the cathode 13 and the anode 14 is precisely determined as desired. Since this precise determination of this space is essential to the proper functioning of the cell, the value of my novel method of initially assembling the ring 5 and the stem 15 is obvious.

I will now describe the use of my improved tool T for adjusting the stem 15 relative to the ring 5 in order to redetermine the space between the cathode 13 and the anode 14 when consumption of the anode 14 in use has increased the space

between the cathode 13 and the anode 14. When the casing 12 has been removed and the electric circuit to the anode 14 has been opened, the tool T is mounted in operative position by connecting lugs 19 and latches 20 (Fig. 2); the rod 21 is screwed down to dispose the ring 26 about the upper end 15-b of the stem 15; the ring 26 is then clamped on the stem 15 by functioning of the cam 32; further depression of the rod 21 brings the head 23 into contact with the stem 15; depression of head 23 by rod 21 presses the stem through the ring 5 and eventually carries the anode 14 downwardly to contact the bottom of the cell 1. The movement of rod 21 is then reversed to raise the head 23 into contact with the collar 24. Further upward movement of the rod 21 causes raising of the stem 15 and movement upwardly of the anode 14. It is obvious that the rod 21 can be calibrated so that a determined rotation thereof will precisely determine the space between the cathode 13 and the anode 14.

It is to be particularly noted that to utilize my improved tool T only the latches 20 have to be provided for each of the considerable number of anode stems in a cell, which constitutes an important saving in capital cost of the cell. Experience has proved that a cell of 112 anode stems can be properly serviced to provide an anode-cathode space of one quarter of an inch, by one operator using my improved tool in less than one hour's time.

The particularly valuable improvement of my invention consists in the fact that this adjustment may be done while the cell remains in operation. As above explained, a cell contains a considerable number of anodes, for instance 112. As illustrated in Fig. 5, four anodes can be connected to the switch 102; so that when this switch is open only four anodes out of the hundred or more are not operating and the slight increase in current of about 4% which occurs in all of the other anodes which are still in operation will not cause any change in the functioning of the cell which will continue to produce during all of the time of the adjustment of the anode-cathode gaps of the four anodes. When these four anodes have been adjusted, they are again switched into the circuit and then four other anodes can be adjusted, and so on for all of those in the cell.

Contrary to what might be expected, movements of the graphite rod through the graphite ring do not produce any noticeable wear of the ring, and the same rod and ring can be used after several anodes have been consumed.

My improved means for mounting the rod does not introduce any supplementary voltage losses in the electric contacts but in fact it definitely reduces them. The close contact between the electric conductor 7 and the graphite ring 5 which is easily effected (as anyone skilled in the art will understand) is then better than effected by the conventional method of leading the current to the graphite rod by means of a collar.

Moreover, experience has shown that the electrical contact between the graphite rod 15 and the graphite ring 5 has a very small electric resistance. If the graphite rod 15 be mounted in the graphite ring 5 with the correct pressure, the contact resistance R, representing the ratio between the drop of voltage E (in volts) and the current density through the contact D (amp. per sq. in.), will be less than 0.001 ohm per sq. in. It should be particularly emphasized that this resistance does not increase with use, viz. repeated adjustment of the rod in the ring, but remains constant. This is an extremely valuable feature of my improved means for mounting the anode stem for adjustment.

It is obvious that my improved means for mounting the stem is adapted for use in cells in which the cathode and anode are vertically disposed.

Having described my invention, what I claim is:

In a device for adjustably mounting an anode in a gas generating electrolytic cell having a sealing cover with an orifice therein, the combination of a graphite rod of uniform circular cross-section passed loosely through said orifice and having an anode mounted on the end of the rod in the cell; a graphite collar having a circular orifice of uniform cross-section and encompassing said rod exteriorly of the cell; and means for mounting said collar on the cover of the cell in a gas-tight joint, the dimensions of the rod and the collar having the relations expressed in the following formulae:

$$0.00001D \leq D - D'$$

$$0.01D \geq D - D'$$

Δ is approximately 1.79D

H is approximately 0.6D

40 in which D is the outside diameter of the rod, D' is the inside diameter of the collar, Δ is the diameter of the largest circle inscribed on the collar, and H is the distance between the faces of the collar.
